RECLINING CHAIR

Adelard J. Belisle, South Hadley Falls, Mass., assignor to The Berkline Corporation, Chicopee Falls, Mass., a corporation of Tennessee

Application April 23, 1952, Serial No. 283,811

5 Claims. (Cl. 155—105)

1

This invention relates to improvements in chairs and is directed more particularly to improvements in chairs having a seat and back which are tilttable relative to a frame.

A principal object of the invention is the provision of a chair wherein a seat and back are readily tilttable from sitting to reclining positions relative to a frame by the occupant of the chair and a leg rest is swung and projected forwardly accordingly as the seat and back are so moved to the reclining position.

According to the invention, the mechanism for the tilting of the back and seat and operation of the leg rest is simple in form and efficient in operation making it possible to produce the chair economically and not requiring any effort on the part of the occupant of the chair to move the seat and back between upright and reclining positions and simultaneously swinging and projecting the leg rest.

According to special features of the invention, the mechanism for effecting relative movements of the chair parts is so constructed and arranged as to be substantially concealed so as to not detract from the appearance of the chair and is constructed and arranged to occupy small space at the forward part of the chair thus avoiding parts extending beneath the seat and rearwardly thereof.

Chairs of the type to which the invention relates usually comprise a wood frame relative to which the seat and back are movable and it is the practice to upholster the whole to provide a pleasing and artistic appearance and at the same time provide the cushioning and padding for the comfort of the occupant.

In accordance with the invention, the mechanism is of novel form and so associated with the chair parts that when the frame, combined seat and back and leg rest are upholstered the mechanism is not visible.

All of the above objects I accomplish by means of such structure and relative arrangements of parts thereof, as will fully appear by a perusal of the description below and by various specific features which will be hereinafter set forth.

To the above cited and other ends and with the foregoing and various other novel features and advantages and other objects of my invention as will become more readily apparent as the description proceeds, my invention consists in certain novel features of construction and in the combination and arrangement of parts as will be hereinafter more particularly pointed out in the claims hereunto annexed and more fully de-

2

scribed and referred to in connection with the accompanying drawings wherein:

Fig. 1 is a side elevational view of a chair construction embodying the novel features of the invention;

Fig. 2 is a sectional plan view at one side of the chair on the line 2—2 of Fig. 1;

Fig. 3 is a side elevational view of the parts shown in Fig. 2; and

Fig. 4 is a side elevational view of one of the hinge members of the mechanism shown in Figs. 2 and 3.

Referring now to the drawings more in detail, the invention will be fully described.

15 Side frames 2 each include similar forward vertical members 4 and rear vertical members 6 which are secured at lower ends to opposite ends of bottom side rails 8. An intermediate rail 10 has opposite ends connected to the members 4 and 6. Upper connected together members 12 and 14 secured to upper ends 4 and 6 provide arm rests 16.

The side frames are connected together in spaced relation by transverse members such as 25 a stop 18, and stop 20. There may be other transverse members which have opposite ends secured to elements of the side frames. The transverse members will secure the side frames in such a spaced relation as will provide room for a comfortable seat and back therebetween.

30 The construction described constitutes a strong and rigid chair frame of elements which will usually be formed from wood secured together in the usual manner as by screws, nails, gluing and the like. The chair frame will be upholstered with suitable padding and covering material so that it is concealed for purposes of appearance as is usual.

35 A combined seat and back generally designated by 26 includes L-shaped side plates 28 which are secured together in transversely spaced relation by various members such as 30, 32, 34 and a forward strut 36.

40 There may be other transverse members and the elements of the seat and back will be formed from wood and secured to the side parts 28 for strength and rigidity. The seat and back will be upholstered by padding and covering material for concealing of the structural elements and for the comfort of the occupant.

45 Side plates 28 of the combined seat and back are connected to the chair frame for movements of the former relative to the latter between the upright position of the seat and back, as shown 50 in Fig. 1, and a reclining position rearwardly

thereof. Movements of the seat and back from the upright position thereof in the direction of the arrow to reclining position may be accomplished in various ways as by a pivot 30 or a device such as shown in U. S. Patent No. 2,270,430 of January 20, 1942.

A leg rest generally designated by 46 is provided which comprises secured together opposite side members such as 48 and transverse upper and lower members such as 50 and 52. The elements of the leg rest will be formed from wood and said leg rest will be upholstered by padding and covering.

An elongated hinge member 54, as shown in Fig. 4, at each side of the leg rest, have upper ends pivoted at 56 to inner sides of the plates 23, see Figs. 2 and 3. Primary links 58, one for each of the opposite sides of the chair, are pivoted at 60 to blocks 62 secured to members 4, 10 and 14 of the side frames.

Outer ends of links 58 and outer ends of hinge members 54 are pivotally connected at 64.

The hinge members are provided with inner and outer elongated slots 66 and 68. Secondary links 70 are pivoted at one end to the primary links 58, as indicated at 12. Opposite ends of said secondary links 70 are pivotally connected to the side members 48 of the leg rest by screws, bolts or the like 74 secured to said members 48. Said pivot members 74 extend through the slots 66 of the hinge members 54.

Guide members 76 which may be screws, bolts or the like fixed to the side members 48 of the leg rest extend through the other slots 68 of the hinge members.

By means of the pivot members 74 and guide members 76 carried by the opposite side members 48 of the leg rest and which extend through the slots 66 and 68 of the hinge members 54, the leg rest is slideable relative to the said hinge members 54 and towards and away from the seat.

In the sitting position of the seat and back as shown in Fig. 1, the leg rest 46 depends downwardly from the forward end of the seat and between the forward members 4 of the side frames.

As the occupant of the chair leans backwardly, the seat and back tilt in the direction of the arrow to reclining position. As the seat tilts upwardly to the reclining position so as to swing the pivotal connections 58 upwardly, the primary links 58 pivotally connected at 64 to the hinge members are swung upwardly to the position of Fig. 3. During said swinging of the primary links, the pivotal connections 74 of the secondary links 70 with the side members 48 of the leg rest 46 move the leg rest to the right relative to the hinge members and outwardly of the seat.

The pivotal connections 74 sliding in slots 66 of the hinge members 54 bring up against the right hand end of said slots. The outer end of the leg rest is guided for movements relative to the hinge members by guides 76 in the slots 68 of the hinge members.

With the leg rest mounted for sliding movements relative to the hinge members the leg rest is swung to elevated position and projected outwardly simultaneously with the swinging of the seat and back from sitting to reclining position. Conversely, as the seat and back are swung from reclining to sitting or upright position the leg rest is moved downwardly to a position below the forward end of the seat.

It will be noted that the operating mechanism for the leg rest not only is simple and compact

but also is located at the forward part of the chair thereby avoiding parts which extend rearwardly below the seat and adjacent the side frames which interfere with the proper upholstering of the chair.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

20. 1. A chair construction of the reclining type comprising in combination, transversely spaced secured together side frames, a combined seat and back pivoted between said side frames for swinging movements between forward upright sitting and rear reclining positions of an occupant of the chair, a leg rest, and means for moving said leg rest between a substantially vertical position below the forward portion of the seat in sitting position thereof and an elevated and extended substantially horizontal position in reclining position of said seat, said means including members pivotally connected to the forward end of said seat, slideable connections between said leg rest and members and link connections between forward portions of said frame, said leg rest and said members.

2. A chair construction of the reclining type comprising in combination, transversely spaced secured together side frames, a combined seat and back pivoted between said side frames for swinging movements between forward upright sitting and rear reclining positions of an occupant of the chair, a leg rest, transversely spaced elongated hinge members each having one end pivotally connected to opposite sides of the forward portion of said seat, transversely spaced elongated primary links each having one end pivotally connected to upper forward portions of said side frames, opposite ends of each of said primary links pivotally connected to an opposite end of a hinge member, secondary links having one end pivotally connected to a primary link intermediate opposite ends thereof, and pivotal connections between opposite ends of said secondary links and said leg rest, said hinge members provided with elongated slots slidably receiving said pivotal connections for movements of the leg rest relative to said hinge members.

3. A chair construction of the reclining type comprising in combination, transversely spaced secured together side frames, a combined seat and back pivoted between said side frames for swinging movements between forward upright sitting and rear reclining positions of an occupant of the chair, a leg rest, transversely spaced elongated hinge members each having one end pivotally connected to opposite sides of the forward portion of said seat, transversely spaced elongated primary links each having one end pivotally connected to upper forward portions of said side frames, opposite ends of each of said primary links pivotally connected to an opposite end of a hinge member, secondary links having one end pivotally connected to a primary link intermediate opposite ends thereof, and pivotal

connections between opposite ends of said secondary links and said leg rest, said hinge members provided with elongated slots slidably receiving said pivotal connections for movements of the leg rest relative to said hinge members, guide members carried by said leg rest and said hinge members provided with other elongated slots slidably receiving said guides for guiding said leg rest in movements relative to said hinge members.

4. A chair construction of the reclining type, transversely spaced secured together side frames, a combined seat and back structure pivoted between said side frames for swinging movements between forward upright sitting and rear reclining positions of an occupant of the chair, a leg rest having inner and outer ends and longitudinal side members extending therebetween, transversely spaced elongated hinge members each having inner and outer ends, first pivotal connections between inner ends of said hinge members and opposite sides of the forward portion of the seat, transversely spaced elongated primary links having inner and outer ends, second pivotal connections between inner ends of said primary links and forward portions of said side frames, said side members of the leg rest having longitudinally spaced pivot members extending laterally therefrom, said hinge members having relatively spaced elongated slots therealong and slidable on said pivot members for sliding of said foot rest relative to the hinge members between an inner vertical position thereof in sitting position of the seat and a relatively more horizontal and extended position thereof in reclining position of the seat, third pivotal connections between outer ends of said primary links and outer ends of said hinge members for swinging said hinge members between a vertically disposed position in sitting position of the seat and a relatively more horizontal position in reclining position thereof, secondary links each having one end thereof pivotally connected to and intermediate the opposite ends of a primary link and an opposite end swingable on a pivot member of a side member of the leg rest to slide the leg rest to extended position relative to the hinge member as the primary links swing the hinge members to said relatively more horizontal position.

5. A reclining chair construction of the type wherein a leg rest is simultaneously swung upwardly and projected outwardly and forwardly

of a seat as the seat moves from forward sitting to rear reclining position comprising, a frame structure including transversely spaced secured together side frames, a supporting structure including a seat and a back and swingable connections between said structure and side frame for swinging of said structure between forward sitting and rear reclining positions of an occupant of the chair, an elongated leg rest, elongated hinge means having inner and outer ends, first pivotal connections between the inner end of said hinge means and forward portion of the seat for swinging between a vertical position below the forward portion of the seat in sitting position thereof and a relatively more horizontal position forwardly of said seat in reclining position of said seat, elongated primary link means having inner and outer ends, second pivotal connections between inner ends of said primary link means and a forward portion of said frame structure, said leg rest provided with inner and outer longitudinally spaced pivot means, said hinge means provided with longitudinally spaced elongated slots receiving said pivot means for sliding of said leg rest thereon between an inner vertical position in sitting position of the seat and a forward relatively horizontal projected position in reclining position of said seat, third pivotal connections between the outer end of the primary link means and the outer end of said hinge means for swinging of the latter between vertical and relatively horizontal positions thereof, secondary link means having one end pivotally connected to and intermediate inner and outer ends of the primary link means and an opposite end pivotally connected to the inner pivot means of the leg rest whereby to slide the leg rest forwardly relative to the hinge means to projected position as the primary link means swings the hinge means from vertical to horizontal position in movement of the seat from sitting to reclining position.

ADELARD J. BELISLE.
